UNITED STATES PATENT OFFICE.

JOHN W. BROWN, JR., OF COLUMBUS, OHIO, AND LESTER McCULLOUGH, OF CHICAGO, ILLINOIS, ASSIGNORS TO THE JOHN W. BROWN MANUFACTURING COMPANY, OF COLUMBUS, OHIO, A CORPORATION OF OHIO.

DESIGN FOR AN AUTOMOBILE-LAMP.

50,184.

Specification for Design.

Patented Jan. 16, 1917.

Application filed November 13, 1916. Serial No. 131,155. Term of patent 7 years.

To all whom it may concern:

Be it known that we, JOHN W. BROWN, Jr., residing at Columbus, in the county of Franklin and State of Ohio, and LESTER McCULLOUGH, residing at Chicago, in the county of Cook and State of Illinois, have invented a new, original, and ornamental Design for Automobile-Lamps, of which the following is a specification, reference being had to the accompanying drawings, forming part thereof.

We claim:

The ornamental design for an automobile lamp, as shown.

JOHN W. BROWN, JR.
LESTER McCULLOUGH.

Witnesses for Brown:

WALTER E. S. BOCK,
A. L. PHELPS.

Witnesses for McCullough:

MYRTLE R. McCULLOUGH,
ALICE GARRISON.
